UNITED STATES PATENT OFFICE.

A. H. VAN GIESON, OF NEWARK, NEW JERSEY.

IMPROVED LEATHER-SPLITTING MACHINE.

Specification forming part of Letters Patent No. 35,850, dated July 8, 1862.

To all whom it may concern:

Be it known that I, A. H. VAN GIESON, of Newark, in the county of Essex and State of New Jersey, have invented an Improved Machine for Splitting Leather, of which the following is a specification.

The improvements consist in, first, the combination of a peculiar-formed bed or table, hereinafter described, over which the leather is drawn before coming in contact with the knife which splits it, a gage directly in front of the edge of the knife, another gage immediately in rear of it, one of which gages is adjustable for a purpose hereinafter stated, a set of weighted or loaded fingers which press the leather down near to the bed, thus smoothing or flattening it out and causing it to press equally on all parts of the gage-edge, and a continuous roller which operates in a similar manner to aid in producing the same result, the whole being arranged and operated substantially as hereinafter set forth; second, the combination of the said bed, gages, fingers, and roller with a knife for splitting the leather and a roller for drawing it through the machine, and a friction roller to prevent the slipping of the leather on the drawing-roller, as hereinafter described.

In the drawings, Figure 1 is a plan of my improved machine. Fig. 2 is an end elevation of the same, showing the end which is at the left in Fig. 1. Fig. 3 is a transverse sectional elevation showing the parts to the right of the center in Fig. 1.

1 is the bed, the construction of which is clearly shown in Figs. 3 and 4. 22 are the fingers, which press the leather down toward the bed. They are held down by the weighted levers 33, which are weighted or loaded at their outer ends by means of weights 44. 5 is the continuous roller, which holds the leather down to the bed before the fingers begin to act upon it. 6 is the gage forward of the knife. It is made adjustable by means of screws 24, working in the bed and bearing against the rear of the said gage, and the said gage is made as straight as possible, as is also the knife 7. 8 is the bed in which the knife vibrates. 9 is the drawing-roller, which draws the leather through the machine. 10 is a friction-roller, used to prevent the leather from

slipping on the roller 9. The thickness of the leather cut off from the main part is determined by the height of the gage 6, which is regulated by the screws 24. If desirable, the rear gage may be made adjustable in the same manner as the front one, or the knife may be similarly arranged; but I prefer making them as described.

11 is the journal on which the roller 10 is hung in such a manner that it may be thrown back out of way when it is desirable to do so. The roller 10 is held down against the leather by means of the lever 12, which catches into a notch made to receive it in the arm 13. The fingers 22 are adjustable in the same manner by means of the lever 14 and arm 15.

Motion is communicated to the different parts of the machine by means of a belt acting on the pulley 16 and driving the shaft on which it is hung. Through this shaft the motion is carried to the double cam 17, which draws out the rod 20, to which the knife 7 is attached, toward the said cam, and after the extreme projection of the cam passes by the roller 18 the knife is thrown or drawn in the opposite direction by means of the spring 19, thus producing a reciprocating motion of the knife 7. The motion is also communicated from the shaft on which the pulley 16 is hung to the shaft on which the wheel or pulley 21 is hung, and from thence by means of the wheels 22 and 23 it is communicated to the driving-roller 9. The leather in passing through the machine is first introduced between the bed 1 and the roller 5, where it comes in contact with and is drawn over the corrugations shown on the bed in Fig. 4, which, as is evident from their form and direction, will spread it out laterally when passing over the ridge in the center between the roller 5 and the fingers 22, which fingers cause it to bear equally on the edge of the gage 6, so that the leather will not be crushed or compressed, as it is in other machines, by the direct pressure applied to it immediately over the knife, or nearly so, but on the other hand will be by tension drawn down to the gage 6 with sufficient force to make the under surface assume the form of a perfect or nearly perfect plane. Thus it will be seen that it will make no material difference whether the leather is of even

thickness or not; but as the quality of work done in the machines depends very much on this circumstance, the avoidance of this cause of difficulty is a matter of great importance.

If crushing or compressing takes place, the leather will be unevenly cut, and by wetting it the unevenness becomes still more apparent. This objectionable feature, which is a matter of great importance when splitting off very thin sheets of leather, is avoided by my improved arrangement of parts when constructed as I have stated.

I claim—

1. The combination of the bed 1, fingers 2, gage 6, gage 25, and roller 5, constructed and operated as described.

2. The combination of the bed 1, fingers 2, gage 6, gage 25, and roller 5 with the knife 7 and rollers 9 and 10, as set forth.

A. H. VAN GIESON.
